UNITED STATES PATENT OFFICE

ARTURO GÉNOVA, OF MADRID, SPAIN

METHOD FOR RESCUING THE CREWS OF SUBMARINE BOATS

Application filed December 27, 1930, Serial No. 505,170, and in Spain December 27, 1929.

The object of the present invention is to make it possible to bring crews shut up in a submarine boat to the surface of the sea. By means of the invention it is possible to rescue the crews in an enclosed manner from the greatest depths to which the boat can sink without collapsing. In any case, it is not necessary to employ divers, and the submerged men are not subjected to the pressure or temperature of the water. Moreover, no subsequent medical treatment of any kind is required, while blood clots, colds, etc. are avoided. The military or naval faculty of the ship is not affected detrimentally in any way. The invention can be fitted to the greater part of existing ships. Frequent life saving practice can be carried out without danger to the safety of the ship or of its personnel. Its installation on board permits all the individual respiratory appliances to be dispensed with, which appliances are of doubtful practical use when it is necessary to abandon the ship even in shallow water. The only auxiliary external assistance necessary is a ship of any kind which does not carry any special means whatever. The weight of the installation forming the subject of this invention is compensated for by the removal of the individual life saving appliances mentioned above, and of the telephone buoys at present employed which also become unnecessary.

Fig. 1 is an elevation of a submarine equipped with the life saving device.

Fig. 2 is an enlarged view of the sluice chamber containing a buoy.

In general terms, the system consists in fitting a dismountable sluice chamber to the hatchway; a sluice adapted to receive an elevator or buoy which is attached to the submarine by a cable and travels to the surface containing a man each time, until the boat has been completely cleared.

Sluice.—Formed by two sheets of metal plate generally of semi-circular section, with a fluid tight joint, the mutual joint being reinforced if necessary by hoops or straps. It may also be formed by joining together one or more hoops or collars also made of metal plate, and coupled together also with fluid

tight joints. The joints of one or the other method of making the sluice or the like depends upon the shape and dimensions of the space available for storing it in the submarine.

At the upper part of the sluice is formed an opening which can be closed by means of a fluid tight autoclave door in order to permit the entry of a man. At the base is provided an emptying valve and stuffing boxes for the passage of a cable. At its middle portion is provided one or more test cocks, glass windows, manometer and a valve communicating with the hydraulic system, which will be mentioned hereinafter. The structure of the sluice will conform to that of the submarine so that it can resist the same maximum pressure as the latter.

Elevator.—This is a metal container having the shape of a cylindrical projectile with a lower ogival extension with the object of facilitating its entry into the sluice when a pull is exerted on the cable secured to this end.

This upper base is formed by fluid tight cover or closure which can be operated both from inside and outside the elevator. The dimensions of the elevator will be those necessary to receive a man of normal size. Externally it will have a diameter some cms. less than the inside of the sluice. It will be provided with an external attachment ring bolt with air valves and any accessory devices for giving signals, such as cartridges of calcium, phosphate, "steam boats" (Spanish "botes de humos"), rockets, etc. Its structure is such that it can resist the external pressure corresponding to the maximum depth at which the submarine may lie, but it nevertheless possesses sufficient buoyancy or rising force to enable it to float when loaded with a man.

Cable, hand wheel and stuffing boxes.—Cable of superflexible steel with telephone core. The latter will serve as conductor in order to make spoken communication possible between the interior of the elevator and the submarine. The operation of covering or spinning the cable will be made by means of a small hand wheel also mounted inside the boat with no further special provision than

a simple device for the electrical connections of the telephone. The stuffing box for the passage of the cable differs from those in current use by the feature that it is formed by two bodies rotatable the internal one on account of the sliding movement of the cable itself through it due to the helical form of its surface. The joint, which need not be absolutely fluid tight, is made by means of two portions of plastic material one of which is placed between the cable and the movable part and the other between the latter and the fixed part.

Equipment of the hatchway.—It will be necessary to modify slightly the method of closure of the hatchway mounted initially on the submarine. Primarily, the cover will be balanced by means of counterweights.

Between the superstructure layer and the resisting shell will be mounted a small cylinder having its piston connected with the cover of the hatchway by an existing pivotal system formed by piston rod and connecting bar. By connecting the dead spaces alternatively with the sea and with the atmosphere inside the submarine, the piston will be moved one way or the other, thus lifting or closing the cover of the hatchway. The same result will be obtained with the local bilge pump with the addition of a certain number of valves and tubes, or by means of compressed air, the installation being connected to the compressed air network of the ship. Finally a valve will be provided in the tube of the hatchway for flooding the sluice and another valve for removing the air.

Operation.—Failing all attempts to raise the damaged submarine to the surface under its own power, the crew will proceed to mount in the available hatchways the sheets or hoops described above in order to form a sluice, and they will naturally leave the elevator within the sluice. The first man will enter and will close the cover after him. After having also closed the autoclave door of the sluice, the latter will be flooded by manipulating suitable valves.

When it has been filled and its pressure equals that of the sea, the hatchway will be opened by any of the three means mentioned in the previous paragraph. Upon lifting the cover, the cable will unwind so that the elevator, on account of its buoyancy, will rise to the surface.

Upon reaching the surface, if the state of the sea permits it, the occupant will open the cover and by means of the signals, lights, rockets or flares with which he is provided, he will attract the attention of the nearest ship. If the state of the sea is such as to make the elevator liable to be flooded, its occupant can remain enclosed in the latter until he is seen, without running the risk of suffocation; for this purpose the elevator is

provided with respirators for use in such a case.

He will communicate by telephone with his companions below, and will inform them when help arrives.

When a ship comes on the scene, it will only be necessary to attach the buoy by its ring bolt to the washboard after which the occupant will be removed and when the cover has been closed and the fastening replaced, those down below will have to wind up the cable so as to make the elevator return to the sluice.

By the reverse operation of valves, the hatchway will be closed and the sluice emptied in order to permit a second man to enter, after which the same operations described above will be repeated with this second man in the elevator. The latter can thus also be rescued.

When the elevator returns for the last time, the last man will cut the cable near the stuffing box.

After having arranged the suitable system of valves, he will enter the sluice, close its door and when necessary will open a last slow flooding valve, the hand wheel of which will be provided within the sluice in the false hatchway. After communicating with the hydraulic arrangement of its cover, he will enclose himself with tranquility in the elevator with the certainty that in a few minutes time the chamber containing him will float from the sluice until it presses against the cover of the hatchway and will thus assist the action of the piston which will then raise the cover, after which the elevator will rise rapidly to the surface where it will be seen.

What I claim is:

A device for escape from submarines comprising a chamber arranged within the submarine craft and composed of two semi-cylindrical parts adapted to be separated to afford access to the chamber, a movable closure for the top of the chamber, a buoyant occupant-receiving member located in said chamber, a cable carried by the buoyant member and extending through the wall of said chamber, and means for actuating said chamber.

In testimony whereof I have signed my name to this specification.
